(57) **CLAIM**

The ornamental design for a portable handheld vaporizing device, as shown and described.

DESCRIPTION

FIG. 1 is a top perspective view of the portable handheld vaporizing device showing our new design with the mouth piece component shown in a raised position;

FIG. 2 is another top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a top perspective view of the portable handheld vaporizing device with the mouth piece component shown in a lowered position;

FIG. 9 is another top perspective view thereof;

FIG. 10 is a front elevational view thereof;

FIG. 11 is a rear elevational view thereof;

FIG. 12 is a top plan view thereof;

FIG. 13 is a left side elevational view thereof;

FIG. 14 is a top perspective view of the draw tube portion of the portable handheld vaporizing device shown in a raised position, with the mouth piece component and vaporizer removed;

FIG. 15 is a rear elevational view thereof;

FIG. 16 is a left side elevational view thereof;
FIG. 17 is a top plan view thereof;
FIG. 18 is a bottom plan view thereof;
FIG. 19 is a top perspective view of the draw tube component of the portable handheld vaporizing device shown in the lowered position;
FIG. 20 is a front elevational view thereof;
FIG. 21 is a front perspective view of the mouth piece component of the portable handheld vaporizing device shown in a raised position with the vaporizer removed;
FIG. 22 is a rear elevational view thereof;

FIG. 23 is a left side elevational view thereof;
FIG. 24 is a top plan view thereof; and,
FIG. 25 is a front perspective view of the mouth piece component of the portable handheld vaporizing device shown in a lowered position with the vaporizer removed.
The broken lines showing in FIGS. 6 and 18 on the portable handheld vaporizing device are included for the purpose of illustrating unclaimed features and form no part of the claimed design.
